(57) **CLAIM**

The ornamental design for a currency clip apparatus, as shown and described.

DESCRIPTION

FIG. 1 is a back view of the currency clip apparatus, showing, in particular the ornamental design thereof;

FIG. 2 is a front view thereof;

FIG. 3 is a side elevational view thereof; and,

FIG. 4 is a top elevational view thereof.

Applicant submits that the two clips are identical and symmetrical about a longitudinal axis thereof.
